UNITED STATES PATENT OFFICE.

CHARLES DIEHL, OF PERU, INDIANA.

VALVE-GRINDING MACHINE.

Application filed October 28, 1921. Serial No. 511,216.

To all whom it may concern:

Be it known that I, CHARLES DIEHL, a citizen of the United States, residing at Peru, in the county of Miami and State of Indiana, have invented a new and useful Valve-Grinding Machine, of which the following is a specification.

This invention relates to a valve grinding machine, and more particularly to a machine 10 constructed to facilitate the grinding of valves by grinding a number of valves simultaneously.

The primary object of the invention is to provide means for rotating the valves with 15 respect to their cages in which the valves are supported, the weight of the respective valve cages being sufficient to cause the valve cages to rotate with their valves when the valves move in one direction, but cause the valve 20 cages to move with respect to the valve members, when the valve members are moved in a reverse direction.

Another object of the invention is to provide means for centering the valve with respect to its cage and seat, to insure a true 25 grinding of the valve.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, may be made within the 35 scope of what is claimed, without departing from the spirit of the invention.

Referring to the drawings:

Figure 1 is a side elevational view of a machine constructed in accordance with the 40 present invention.

Figure 2 is a plan view of the same.

Figure 3 is a sectional view taken on line 3—3 of Figure 1.

Figure 4 is an enlarged detail view 45 closing the connection between an operating rod and valve stem.

Figure 5 is a sectional view taken on line 5—5 of Figure 4.

Figure 6 is a sectional view taken on line 50 6—6 of Figure 5.

Referring to the drawings in detail, the reference character 5 designates the base of the machine, to which is secured the frame indicated generally by the reference character 6, and which embodies the sections 7 and 55 8 respectively.

Supports 9 extend upwardly from the base as clearly shown by Figure 1 of the drawings, each support being provided with a vertically disposed bore designed to accommodate a centering pin indicated at 10, suitable means such as the set screw 11 being provided to secure the centering pin in its positions of adjustment. A transversely extending pin 12 forms a part of each centering pin 10, and by means of which the centering pins may be moved vertically within the bores of the supports.

Bearing members 13 are formed on the upper portion of the frame, and these bearing members support the operating rods 14, which have heads 15 formed at the lower ends thereof, which heads form the upper sections of the universal joint employed in connecting the operating rods 14 and the 75 valve stems carrying the valves under operation.

Pinions 16 are carried at the upper ends of the operating rods 14 and are in mesh with the rack bar 17, which moves along the 80 upper edge of the frame, as clearly shown by Figure 1 of the drawings. This rack bar is formed with spaced ears 18 extending upwardly therefrom at one end thereof, which ears provide means to connect the link 19 to 85 the rack bar.

A pulley 20 is mounted at one end of the frame and receives motion from the pulley 21 as through the belt 22, the pulley 21 receiving motion from the shaft 23 which is 90 rotated by the pulley 24 that is directly connected with the motor shaft 25, as through the medium of the belt 26. The link 19 is eccentrically connected to the pulley 20, whereupon movement of the pulley 95 20 causes the rack bar 17 to reciprocate, to the end that the operating rods 14 are oscillated.

As shown, each of the heads 15 is provided with a transversely extending opening, 100 and an opening 27 extending through the lower portion thereof, the opening 27 being designed to accommodate the upper extremity of the valve stem, indicated at 28, which valve stem has connection with a block 29 105 supported within the transversely extending opening of the head. The block 29 is formed with a central opening, and a set screw 30 operating through the block to grip the valve stem and secure the same within the 110 block. Thus it will be seen that due to this construction, the valve stem will automati-

cally center itself with respect to the operating rod associated therewith to properly grind the valve formed at the opposed end of the stem.

5 In the use of the device, the valves and their cages, the latter being indicated at 31, are positioned in the machine in a manner as illustrated by Figure 3 of the drawings, the valve heads being positioned on the centering pins 10. It follows that as the machine is operated, the valves are oscillated, carrying the valve cages, the weights of the cages being sufficient to cause the cages to move with the valves.

10 15 When the valves reverse movement, during the oscillation thereof, it is obvious that the cages will slide over the valves to grind the contacting surfaces.

Having thus described the invention, what 20 is claimed as new is:—

1. A valve grinding machine including a base, a frame supported by the base, operating rods extending through the frame and carrying pinions on the upper ends thereof, 25 a reciprocable rack bar movable along the upper surface of the frame and contacting with the pinions to move the operating rods, supports mounted on the base, a centering pin mounted in each support, means for connecting a valve to the respective operating

30 rods, said valve adapted to engage the centering pin associated therewith, and means for reciprocating the rack bar.

2. A valve grinding machine including a base, a frame supported by the base, centering pins adjustable on the base, operating rods carried by the frame, said operating rods adapted to cooperate with the centering pins for supporting valve members and their cages, and means for oscillating the operating rods to cause the valve cages to move with respect to their valves. 35 40

3. A valve grinding machine including a base, a frame supported above the base, operating rods supported by the frame, universal joints at the lower ends of the operating rods, said universal joints providing means to connect valves thereto, centering pins carried by the base and contacting with valves for holding the valves in vertical positions with respect to the valve cages supported thereby, and means for causing the valves to oscillate under the valve cages. 45 50

In testimony that I claim the foregoing as my own, I have hereto affixed my signature in the presence of two witnesses.

CHARLES DIEHL.
